DRESSING MECHANISM FOR GRINDING WHEELS

Ira J. Snader, Detroit, Mich., assignor to Ex-Cell-O Corporation, Detroit, Mich., a corporation of Michigan

Original application December 2, 1937, Serial No. 177,693, now Patent No. 2,251,961, dated August 12, 1941. Divided and this application August 3, 1940, Serial No. 350,362

5 Claims. (Cl. 125—11)

The present invention relates to improvements in dressing mechanisms for grinding wheels, and has particular reference to such mechanisms adapted for use in machine tools.

One of the objects of the invention is to provide a novel dressing mechanism which is conveniently and accurately adjustable to provide the grinding wheel selectively with different cutting contours adapted to grind various thread forms, such as U. S. standard, sharp V, acme and buttress.

Another object is to provide a new and improved dressing mechanism in which each dressing feed increment toward the grinding wheel is accompanied by a simultaneous compensatory feed increment of the wheel toward the work so as to compensate automatically for reduction in size of the wheel through dressing.

A further object resides in the provision of a novel dressing mechanism which is adjustable relative to the grinding wheel and which may be quickly actuated into and out of dressing position without disturbing the dressing adjustment.

Other objects and advantages will become apparent as the description proceeds.

Figure 1 is a left end elevational view of a machine provided with a dressing mechanism embodying the features of my invention.

Fig. 2 is a fragmentary plan view on an enlarged scale and partially in horizontal section of the dressing mechanism.

Fig. 3 is a diagrammatic representation of the hydraulic circuits for the dressing mechanism.

Fig. 4 is a detail sectional view taken substantially along line 4—4 of Fig. 2.

Fig. 5 is a longitudinal vertical sectional view taken substantially along line 5—5 of Fig. 6.

Fig. 6 is a transverse vertical sectional view taken substantially along line 6—6 of Fig. 5.

Fig. 7 is a fragmentary view of the dressing mechanism illustrated in Fig. 2.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

The dressing mechanism constituting the exemplary embodiment of the present invention, although not limited in its broad aspects to any particular type of grinding machine, is espe-

cially suited, and is shown, applied to a machine adapted for grinding internal and external screw threads. Such a machine is disclosed in detail in my copending application, Serial No. 177,693, filed December 2, 1937, now Patent No. 2,251,961, of which the present application is a division.

The machine comprises a base 1 having a front section 2 and a rearwardly extending section 3 at one end. The top of the base section 2 is formed with longitudinal ways 4 on which a work carriage or work table 5 is suitably mounted for reciprocation. A headstock 6 is mounted on the work table 5 and is adapted to support a work blank (not shown) for rotation and for longitudinal reciprocation along the ways 4.

The top of the rear base section 3 is adapted to support a tool fixture 7 for cross feed and adjustment in a direction transversely of the ways 4. The fixture 7 has a power driven spindle 8 supporting a suitable grinding element or wheel 9 for cooperative engagement of the work. The dressing mechanism of Figs. 1 to 5, identified generally by the numeral 10 is mounted on the tool fixture 7 in position to shape and true the grinding wheel in accordance with the requirements of the work to be ground. For further details of the machine reference may be had to my aforesaid copending application.

The dressing mechanism 10 is mounted on a cross slide 11 for automatic adjustment transversely of the grinding wheel axis, and comprises a plurality of independently adjustable dressing units 12, 13 and 14 automatically operable to true the various faces of the cutting contour of the external grinding wheel 9.

In its preferred construction, the dressing mechanism 10 comprises a base bracket 15 mounted on the top of the cross slide 11 for movement therewith. A dresser slide 16 is mounted on the bracket 15 for rectilinear feed transversely of the tool spindle 8, and is formed on the top with a plurality of arcuate guideways 17 concentric about a vertical axis 18 in the central plane of the grinding wheel 9. The dressing units 12, 13 and 14 are mounted in the guideways 17 for selective adjustment into different angular positions relative to the grinding wheel 9 depending on the form and character of the thread to be ground and hence the contour of the wheel. It will be understood that the dressing units may be arranged for various thread forms, such as U. S. standard, sharp V, acme and modified buttress. In the present instance, the dressing units 55 are shown arranged respectively to true the faces

of a wheel contour having oppositely inclined side faces 19 and 20 and a peripheral face 21.

Preferably, the dressing units 12, 13 and 14 are closely similar in construction so that a description of the unit 14 will suffice for all. This unit comprises a body bracket 22 (Fig. 4) having an arcuate guideway 23 slidable on one of the guides 17. A gear pinion 24 is journaled in the outer end of the bracket 22, and meshes with a gear segment 25 on the slide 16 and concentric with the guide 17. Two screws 26 are threaded through opposite ends of an arm 27, rigid intermediate its ends with the pinion 24, for engagement with the bracket 22. The pinion 24 is adapted to be lifted out of engagement with the segment 25 to permit free movement of the bracket 22 along the guide 17 for rough adjustment. Fine adjustment is obtained by turning the screws 26 oppositely to rotate the pinion 24 while in mesh with the segment 25. A suitable arcuate scale 28 is provided on the slide 16 to indicate the position of adjustment.

The body bracket 22 is adapted to be locked in position of adjustment by a gib block 29 which is disposed in a recess 30 in the guideway 23 for clamping engagement with the guide 17, and which is threaded on a screw 31 journaled in and extending to the front of the bracket 22 and there provided with a hand knob 32.

Fixed on the bracket 22 (as shown in the sectional view of the dressing unit 13) is a cylinder 33 which is closed at one end by a plate 34 and has an elongated bearing sleeve 35 at the other end. A piston 36 is reciprocable in the cylinder 33 and is nonrotatably fixed on a rod 37 extending slidably through the sleeve 35. A pin 38 fixed in the cylinder 33 has a close sliding fit with the piston 36 to hold the latter against rotation in the cylinder 33. The outer end of the rod 37 is provided with a head 39 in which a suitable dressing tool 40 is secured for radial adjustment. Fluid under pressure is adapted to be supplied alternately from lines 41 and 42 (Fig. 3) opening to opposite ends of the cylinder 33 to reciprocate the piston 36 and thereby move the tool 40 in a dressing cut across the intended face of the grinding wheel 9.

The dresser slide 16 may be fed either manually, or automatically by hydraulic means once for each reciprocation of the work table 5. The feed means (see Figs. 5 and 6) comprises a screw 43 rotatably anchored against endwise movement in antifriction bearings 44 in the base bracket 15, and extending in threaded engagement with a fixed nut 45 on the underside of the slide 16. A worm wheel 46 is fixed on the screw 43 and meshes with a worm 47 on a transverse shaft 48 supported in antifriction bearings 49 in the side of the bracket 15. The outer end of the shaft 48 extends through a housing 50, and is provided with a hand wheel 51. A ratchet wheel 52 is fixed on the shaft 48 within the housing 50, and is adapted for engagement by a pawl 53 pivotal on the upper end of a vertical lever 54. The lower end of the lever 54 is rigid with a gear segment 55 which is freely rotatable on the shaft 48, and which meshes with a longitudinal gear rack 56 on a piston rod 57. The rod 57 is connected to a piston 58 reciprocable in a cylinder 59 mounted within the bracket 15. Fluid pressure is adapted to be supplied alternately through lines 60 and 61 to opposite ends of the cylinder 59 to effect reciprocation of the pawl 53. The length of the automatic stroke of the pawl 53 and hence the dresser feed incre-

ment is subject to adjustment by means of a stop screw 62 which is adjustably threaded through one wall of the bracket 15 and limits the outward movement of the piston rod 57.

5 A hand lever 63 is journaled in one wall of the bracket 15, and has an arm 63a adapted for engagement with a pin 64 on the pawl 53 to lift the latter out of engagement with the ratchet wheel 52 when it is desired to feed the slide 16 manually, for example, to retract the slide for the purpose of mounting a new grinding wheel 9.

10 For each dressing feed increment, a like approach feed increment is imparted to the tool cross slide 11 to compensate for the reduced diameter of the grinding wheel 9. To this end, a second cylinder 65 is connected in parallel with the cylinder 59 across the fluid lines 60 and 61. A piston 66 is reciprocable in the cylinder 65, the two pistons 58 and 66 being operable simultaneously. The piston 66 is operatively connected through a feed mechanism to a worm 67 for adjusting the cross slide 11. This feed mechanism may be the same as the feed mechanism actuated by the piston 58 for rotating the worm 47 in the feed drive for the dressing mechanism, and hence is not separately shown in detail.

20 The worm 67 meshes with a worm wheel 68 secured to a nut 69. This nut is rotatably confined by a plate 70 in a bracket 71 rigidly secured to the under side of the cross slide. A cross feed screw 72 is threaded through the nut 69 and is adapted for connection to suitable drive means (not shown). When the dressing mechanism 10 is idle, the worm 67 serves to hold the nut 69 against rotation so that actuation of the screw 72 will effect feed adjustment of the cross slide 11 and the grinding wheel 9 thereon. When the piston 58 is actuated to impart a dressing feed increment to the slide 16, the worm 67 is operated to rotate the nut 69 and thereby impart a like increment to the tool slide 11 to compensate for the stock to be removed from the grinding wheel 9 in the dressing operation.

Hydraulic circuit

30 The lines 60 and 61 to the dresser feed cylinder 59 and the compensatory cross feed cylinder 65 are adapted to be reversibly connected, through a hand valve 73 directly to a fluid pressure line 74 and an exhaust line 75. When not in use, the valve 73 is held in position by an internal spring (not shown).

40 The three cylinders 33 for the dressing units 12, 13 and 14 are connected in series for successive operation to the lines 41 and 42. More particularly, the line 41 opens to one end of the first cylinder 33. A line 76 adapted to be opened by the associated piston 36 when the latter reaches the end of its stroke in one direction is connected through a by-pass check valve 77 to the line 41 and opens to the inner end of the second cylinder 33. Another line 78 adapted to be opened by the associated piston 36 when the latter reaches the outer end of its stroke is connected through a by-pass check valve 79 to the line 76 and opens to the outer end of the third cylinder 33. Similarly, the line 42 opens to the inner end of the third cylinder 33. A line 80 adapted to be opened by the third piston 36 when the latter reaches its outermost position is connected through a by-pass check valve 81 to the line 42 and opens to the outer end of the second cylinder 33. A line 82 adapted to be opened by the second piston 36 when the latter reaches its innermost position is connected through a by-

pass check valve 83 to the line 80 and opens to the outer end of the first cylinder 33. All of the cylinder lines open to the cylinders at the top so as to permit removal of air.

It will be evident that when pressure fluid is supplied to the line 41, the first tool 40 will dress one inclined face 19, then the second tool 40 will dress the peripheral face 21, and finally the third tool 40 will dress the other inclined face 20. The fluid from the other ends of the cylinders will exhaust freely through an open exhaust connection common to all of the cylinders and comprising the line 82, the check valve 83, the line 80 and the check valve 81 to the line 42. When pressure fluid is supplied to the line 42, the sequence is reversed, with the tools 40 moving in the opposite directions. By reason of the aforesaid arrangement of check valves, substantially all residual fluid is exhausted and accumulating air is removed without the loss of liquid fluid.

The two lines 41 and 42 are adapted to be reversibly connected by a hand valve 84 at the rear of the machine to two lines 85 and 86, and the latter are adapted to be reversibly connected by a hand valve 87 to a fluid pressure line 88 and the exhaust line 75.

The hand valve 84, which is used while setting the dressing mechanism 10 to a new grinding wheel 9, is normally urged into one position by spring means (not shown) to maintain the tools when not in use away from the wheel. Similarly, the valve 87 is normally held in one position by pressure fluid from the line 88.

An adjustable orifice valve 89 is interposed in the exhaust line 75 at the outlet side of the valve 87 to meter the fluid discharged from the dressing mechanism 10.

In operation the grinding wheel 9 for external grinding is suitably contoured by the dressing mechanism 10 to cut the desired thread form, for example, U. S. standard, sharp V, acme or buttress. The dressing mechanism 10 may be advanced into operative relation to the wheel 9 by repeatedly reversing the hand valve 73. Operation of the dressing units 12, 13 and 14 is effected by the hand valve 87 at the front of the machine or the hand valve 84 at the rear of the machine, and the rate of dressing tool movement is under the control of the adjustable orifice 89.

For redressing the wheel 9 to compensate for wear or to redefine the cutting contour, the valve 73 is actuated to advance the dressing mechanism 10 to the desired extent toward the wheel, and then the dressing units 12, 13 and 14 are actuated as before. An equal feed is simultaneously imparted to the slide 11 to compensate for the reduced diameter of the wheel 9, and thereby maintain the initial gauge setting.

I claim as my invention:

1. In a machine tool, in combination, a base, a support slidable on said base, a tool spindle mounted on and extending substantially transversely of said support and adapted to support a grinding wheel having a peripheral cutting contour with oppositely inclined side faces and an intermediate peripheral face, a dresser slide mounted on said support for movement transversely of said spindle and formed with arcuate

guide means, a plurality of dressing units mounted for independent adjustment on said guide means and adapted to be positioned respectively to dress said faces, each dressing unit comprising a reciprocating tool and a hydraulic motor for reciprocating said tool, hydraulic means for reversibly supplying fluid under pressure successively to the motors of said units to reciprocate said tools in timed sequence, hydraulically operated means for feeding said slide toward said spindle, and hydraulically operated means operable in synchronism with said last mentioned means to move said support in timed relation to the movement of said slide.

15 2. A dressing mechanism comprising, in combination, a support, an arcuate guideway on said support and formed with a concentric gear segment, a bracket slidably mounted on said guideway, a pinion journaled in said bracket and meshing with said segment, a transverse lever rigid intermediate its ends with said pinion, adjusting screws threaded through opposite ends of said lever into abutting relation with said bracket and being oppositely adjustable to rotate said pinion and being relatively adjustable to secure said pinion in position of adjustment, releasable clamp means for securing said bracket in position of adjustment, a cylinder rigid with said bracket, a piston reciprocable in said cylinder and having a piston rod extending therefrom, and a dressing tool adjustably mounted on the outer end of said rod.

30 3. In a machine tool, in combination, a base, a grinding wheel operatively mounted on said base, wheel dresser means on said base including a plurality of dresser units each having a reciprocable dressing tool and a hydraulic motor for driving said tool, and hydraulic means for supplying fluid under pressure to each of said motors in succession including means controlled by an actuated motor for connecting the next motor to be actuated with the fluid supply.

35 4. In a machine tool, in combination, a base, a grinding wheel operatively mounted on said base, wheel dresser means on said base including a plurality of dresser units each having a reciprocable dressing tool and a reversible hydraulic motor for driving said tool, and hydraulic means for supplying fluid under pressure reversibly to each of said motors in succession including means controlled by an actuated motor for connecting the next motor to be actuated with the fluid supply.

40 5. In a machine tool, in combination, a base, a grinding wheel operatively mounted on said base, wheel dresser means on said base including a plurality of dresser units each having a reciprocable dressing tool and a reversible hydraulic motor for driving said tool, and hydraulic means for supplying fluid under pressure reversibly to each of said motors in succession including means controlled by an actuated motor for connecting the next motor to be actuated with the fluid supply, said motors in either direction of operation discharging to a common exhaust line, and an adjustable orifice in said exhaust line for controlling the rate of movement of said tools.

IRA J. SNADER.
